UNITED STATES PATENT OFFICE

ABRAHAM KANTOR, OF PARIS, FRANCE

POWDER BOX

Application filed September 18, 1930, Serial No. 482,771, and in France September 26, 1929.

The present invention relates to improvements in powder boxes in which the powder is brought to the upper surface of a sieve distributor by the partial rotation of this sieve. The improvements have for the principal object to render such powder boxes more convenient to use, by making them so that they may be manipulated with a single hand, which is not the case when the sieve has to be manipulated according to a movement of rotation as in winding up a watch. The characteristics of the invention are the following:

1. A method of operation of the sieve distributor by means of a knob and return spring means so as to impart to it an alternating rectilinear movement.

2. A method of operation intended to withdraw the movable base which carries the charge or block of powder to free this latter, and after recharging, effecting the raising of the block or charge, so that it comes to rest pressed firmly against the under side of the distributor sieve.

25 The present invention allows of the construction of a powder box with automatic distribution, functioning perfectly and having the greatest facilities for effecting the charging with powder. Indeed, at the moment of opening of the distributor sieve, the system producing the control of the movable base is liberated and the charging with powder can thus be effected without other manipulation.

35 The annexed drawings show by way of example a method of carrying the invention into effect.

In this:

Fig. 1 is a plan view of the open box in its position of use,

Fig. 2 is a section on line A—B of Fig. 1,

Fig. 3 is a plan view of the box in its charging position,

Fig. 4 is a section on the line C—D of Fig. 3.

Fig. 5 is a section on the line E—F of Fig. 3, and

Figs. 6, 7 and 8 are views of details of construction of the box.

50 The box 1 of square, rectangular or other

form is provided with a closing cover 2 having a mirror and mounted on a spring controlled hinge. In the interior of this box is housed the circular receptacle 3 (Fig. 3) intended to receive the block or charge of powder. A movable false base 4 is provided mounted on the spring 5 (Fig. 5) and controlled by two small lateral levers 6 and 7 (Fig. 3) pivoting on pins 8 and 9 in the box, the bent back extremities of which levers are adapted to rest on small lateral pivots 18 of the said base. These two levers 6 and 7 are connected by means of a rod 11 which is controlled by the action of the plate 10 (Fig. 5) forming a spring controlled by a press button 12.

It will readily be seen that when the frame 13 of the sieve distributor 14 is open (Fig. 4), the press button 12 is displaced towards the top under the effect of the plate spring 10, the bottom 4 being thus placed in its lowermost position, as the power of the blade spring 10 is greater than that of the spring 5, the two extremities of the lateral levers 6 and 7 moving down to take up the position shown in Fig. 4. The charging of the block of rice powder into the circular receptacle 3 can then be effected.

If now, the frame 13 provided with the sieve distributor 14 is turned about its hinge and pressed down on to this receptacle 3, this operation causes the displacement of the button 12 towards the bottom and the spring 5 as well as the movable base 4 are liberated, the action of the spring 10 being then neutralized. The spring 5 is adapted then to press the charge of rice powder against the sieve distributor 14.

The sieve 14 can be slidden in the frame 13 and is caused to have an alternating rectilinear movement by means of the button 15 and the return spring 20. This action removes a desired amount of powder from the charge or block which powder passes to the upper surface of the sieve ready for use.

When the charge of rice powder is used up, the levers 6 and 7 come in the position shown in Fig. 2, that is to say the plate or withdrawable base 4 of the receptacle 3 rests against the sieve distributor 14, the spring

5 being relaxed. The pivots 18 slide in slots 19 disposed on each side of the receptacle 3 (Fig. 6).

Two small plates 17 whose curvature corresponds to that of the periphery of the receptacle 3 and each having an inclined slot 16, are provided to close the slots 19 of the receptacle 3 with the upward movement of the pins 18, and thus to prevent losses of rice 10 powder through the slots 19; the two small plates in action are displaced in a path at right angles to the upward movement.

The method of employment of such a powder box is readily understood. It is only 15 necessary to open the cover 2, the interior face of which is provided with a mirror, then to operate the sieve distributor 14 by pressing and releasing alternately the button 15 (Fig. 2). The block of rice powder held 20 pressed against this sieve 14 under the effect of the spring 5 has a certain quantity passed through the small perforations which are disposed therein by the action and collects on the upper surface of the said sieve and 25 can be taken up by means of the puff or pad.

The great advantage of this box resides in the fact that it may be operated with a single hand and the sieve works as a grater, by rectilinear alternating movements in contrast 30 with other kinds of boxes, and it is not necessary to cause the rotation of the sieve to obtain the distribution of the powder.

The automatic descent of the plate or base 4 is effected by the simple turning up of the 35 frame 13 provided with a distributor sieve 14. Indeed, the blade-spring 10 which is more powerful than the spring 5, brings the levers 6 and 7 into play and the base is lowered automatically ready to receive a new 40 block or charge of powder. The simple closing of this frame 13 causes the neutralization of the spring 10 and the base 4 on being raised by the spring 5 causes the compression of the charge of powder against the 45 sieve distributor.

The invention is not limited to the precise forms, shapes or details of construction described as these may be varied to suit particular cases.

50 What I claim and desire to secure by Letters Patent of the United States of America is:—

1. A powder box, comprising a box, a lid to the box, a compartment in the box to receive 55 a block of powder, a distributor sieve located at the top of said compartment, a false base in the said compartment to receive the said block, spring means to press the block against the under side of the distributor sieve, a press button to impart rectilinear movements to the said sieve in one direction, spring means to effect return movements in the opposite direction, and guiding means for the said sieve, for the purposes set forth.

2. A powder box as claimed in claim 1 in which the distributor sieve is mounted to reciprocate in a frame hinged to the box and in which means are provided controlled by the frame for moving the false base towards the bottom of the compartment when the said frame is in the opened position, and for permitting the false base to move upwardly under the action of its spring when the frame is in the closed position for the purposes set forth.

3. A powder box as claimed in claim 1 in which the distributor sieve is mounted to reciprocate in a frame hinged to the box and in which spring means are provided controlled by the frame for moving the false base towards the bottom of the compartment when the said frame is in the opened position, and for permitting the false base to move upwardly under the action of its spring when the frame is in the closed position for the purposes set forth.

4. A powder box as claimed in claim 1 in which the distributor sieve is mounted to reciprocate in a frame hinged to the box and in which spring means are provided controlled by the frame for moving the false base towards the bottom of the compartment when the said frame is in the opened position, and for permitting the false base to move upwardly under the action of its spring when the frame is in the closed position the spring means controlled by the movement of the frame having a power greater than the spring means for effecting the upward movement of the false base for the purposes set forth.

5. A powder box as claimed in claim 1 in which the distributor sieve is mounted to reciprocate in a frame hinged to the box and in which two levers are provided mounted on pivots on the interior facing walls of the box, each of the levers having bent extremities to engage pins mounted on side edges of the false base, the other ends of the levers being united by a transverse rod kept pressed upwardly by a bent spring, the said rod being provided with a button controlled by the frame for moving the false base towards the bottom of the compartment when the said frame is in the opened position, and for permitting the false base to move upwardly under the action of its spring when the frame is in the closed position the said bent spring having a power greater than the spring means for effecting the upward movement of the false base for the purposes set forth.

6. A powder box as claimed in claim 1 in which the distributor sieve is mounted to reciprocate in a frame hinged to the box and in which two levers are provided mounted on pivots on interior facing walls of the box, each of the levers having bent extremities to engage pins mounted on side edges of the false base, slots in the compartment for

guiding the said pins, small curved plates carried by said pins and having inclined slots therein, the other ends of the levers being united by a transverse rod kept pressed upwardly by a bent spring, the said rod being provided with a button controlled by the frame for moving the false base towards the bottom of the compartment when the said frame is in the opened position, and for permitting the false base to move upwardly under the action of its spring when the frame is in the closed position the said bent spring having a power greater than the spring means for effecting the upward movement of the false base for the purposes set forth.

In witness whereof I affix my signature.
ABRAHAM KANTOR.
